(57) **CLAIM**

The ornamental design for a projection module, as shown and described.

DESCRIPTION

FIG. 1 is a perspective view of a projection module showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof showing the projection module mounted on an electronic device; and,

FIG. 9 is a perspective view thereof showing the projection module detached from the electronic device.

The dashed broken lines illustrate portions of the projection module that form no part of the claimed design. The dashed broken lines showing the electronic device in FIG. 8 and FIG. 9 are for the purpose of illustrating environmental structure, and form no part of the claimed design.
